UNITED STATES PATENT OFFICE.

PETER J. FLECK, OF NEW YORK, N. Y.

FOOT-REST FOR RADIATORS.

1,171,779.

Specification of Letters Patent. Patented Feb. 15, 1916.

Application filed May 12, 1915. Serial No. 27,647.

To all whom it may concern:

Be it known that I, PETER J. FLECK, a citizen of the United States, residing at New York city, in the county of New York, State 5 of New York, have invented certain new and useful Improvements in Foot-Rests for Radiators; and I do hereby declare the following to be a full, clear, and exact description of the invention, such as will enable 10 others skilled in the art to which it appertains to make and use the same.

This invention relates to improvements in foot-rests for attachment to radiators or like structures.

15 It is the object of the present invention to provide a foot-rest which may be readily attached to or detached from a radiator structure and which is of a maximum simplicity, it being more specifically the object 20 in this latter connection to provide such a foot-rest wherein the attaching portion comprises merely a single length of resilient wire which may be readily snapped in place on the radiator to provide a sufficiently 25 strong support for the foot engaging portion.

With the above and other objects and advantages in view, the invention resides more particularly in the novel combination, formation and arrangement of parts as more 30 fully hereinafter described and pointed out in the appended claim.

Reference is had to the accompanying drawing, wherein similar characters of reference 35 designate corresponding parts throughout the several views, and in which:

Figure 1 is a perspective view showing the improved device embodied with a radiator structure, the end portion of the structure 40 being broken away to more clearly disclose the invention, Fig. 2 is a central vertical sectional view through the improved device, attached, Fig. 3 is a perspective view of the attaching member of the device and Fig. 4 is a perspective view of a modified 45 form of attaching member.

Referring particularly to the accompanying drawing, there is shown a radiator structure comprising the series of vertical

spaced pipe sections 5 connected at their 50 lower portions by the usual tubular member 6 and connected at their upper portions by the relatively smaller tubular connections 7.

The improved foot-rest as shown in Figs. 55 1 to 3 of the drawing comprises an attaching portion and a foot holding plate detachably engaged therewith. The attaching portion comprises a single length of wire 60 including a straight intermediate section 8 adapted to lie against the pipe sections and having its end portions curved at 9 to resiliently snap around the pipe sections, the end sections 11 of the wire being directed 65 substantially at right angles to the curved portion and terminally bent to provide bowed feet 12 to seat on the lower connecting member 6 of the radiator. The foot engaging member comprises a plate 13 having one edge bent at an acute angle at 13' 70 to hook over the section 8 whereby the plate is secured and having its lower edge bent outwardly at 14 to provide a rest. This plate is preferably of resilient material and the bent edge portion 13' engages the pipe 75 section to resiliently hold the plate at a slight angle to the radiator.

To secure the attaching portion to the radiator, one end portion 9 of the intermediate section is placed around one of the 80 pipes and fits snugly thereagainst and the other portion is snapped into place. By this construction a considerable outward pull 85 may be exerted on the intermediate section without detaching it, while a relatively great pull exerted at one end will detach the portions. Thus as the pull of the plate is distributed all along said section, it will be efficiently held in place.

In Fig. 4, is shown a slight modification 90 wherein the attaching portion is turned upside down and has its end sections 11' hooked at their ends at 15 to hook over the top connection 7.

From the foregoing it is seen that a comparatively simple structure has been provided which will efficiently perform the functions set forth, attention being par-

ticularly directed to the fact that the device comprises only two simple integral members.

What is claimed is:

A foot rest comprising an attaching member comprising a bar having end portions curved to resiliently and detachably engage around sections of a radiator and directed laterally to form arms engaging the hori-

zontal connecting portions of the radiator and a foot engaging portion carried by the bar.

In testimony whereof, I affix my signature, in the presence of two witnesses.

PETER J. FLECK.
